DISAPPEARING TYPE PIN FEED

John E. Euth, Chicago, Ill., assignor to Uarco, Incorporated, a corporation of Illinois

Application August 31, 1955, Serial No. 531,669

6 Claims. (Cl. 197—133)

This invention relates to a pin-type feed unit for use with platens of writing machines and more particularly to a new and improved pin feed of the type in which the pins disappear below the surface of the unit in traveling around it.

Typewriter platens as well as the platens of other business machines are often equipped with a pin feed to engage marginally punched stationery. The platens generally also are provided with the usual friction roller feeds for use with stationery not equipped with punched margins. The particular disappearing pin-type of feed with which this invention is concerned employs a cam for radially reciprocating the pins outwardly from the surface of the platen. The greatest extension of the pins is generally at the line of writing with the pins retracting beyond this line. Such units have, in the past, been equipped generally with a shifting mechanism permitting the turning of the cams so that the pins will extend outwardly at a point away from the line of the stationery passing around the platen so that the platen is equally well usable with either type of stationery referred to.

In the past, considerable difficulty has been encountered with pin feeds of the disappearing type. The most prevalent constructions have employed a cam in the form of a rail serving both to support the pins and to guide them in their radial movement. Some pins have been provided with outwardly extending bosses to engage the rail while in other units the pins have been provided with a notch near their inner end to engage and ride upon the rail. Experience has taught that these pins often catch on the cam rail so that when forced forward by the operator, the pins have been broken and subsequently lost. It is extremely difficult to locate such trouble in advance since the unit is closed except for the openings through which the pins extend, thus giving the manufacturer no chance to observe which of the many pins is causing the difficulty.

It is therefore the principal object of this invention to provide a new and improved disappearing pin-type feed for punched stationery.

Another object of the invention is to provide a unit which may be easily manufactured so as to be smooth running over a greater useful life.

A further object is to provide a disappearing pin-type feed unit in which the pins are provided with bearings guiding their radial movement and a cam and follower structure not subject to the usual seizing or sticking heretofore found in prior art structures.

Other objects, features and advantages of the present invention will be apparent from the following description of a preferred embodiment in which:

Figure 1 is a fragmentary sectional view through the centerline of one end of a platen having the unit of this invention therein;

Figure 2 is a sectional view through the unit taken substantially along line 2—2 in Figure 1 looking toward the pins;

Figure 3 is a sectional view through the unit taken

2

substantially along line 3—3 in Figure 1 looking toward the cam plate;

Figure 4 is a fragmentary sectional view through the unit taken substantially along line 4—4 in Figure 1;

Figure 5 is a fragmentary end elevational view of the unit illustrating the control plates;

Figure 6 is an elevational view of a pin removed from the unit; and

Figure 7 is an end view of the pin illustrated in Figure 6.

As illustrated in Figure 1, the present pin feeding unit is mounted upon the shaft 8 of a typewriter platen carrying an outer rubber sleeve 9 of the platen itself. The outer end portion 8a of the shaft, which is shown as broken, would ordinarily carry a knurled end knob by which the operator could manually turn the platen. While the invention is shown as installed upon a typewriter platen, it is equally applicable to any round platen found in the usual business machines.

In operation, a pin carrier is made to turn with the platen so that the pins are carried with the platen surface and retain their position relative to the platen. The pin carrier has bearings for the pins and revolves next to a stationary cam covering plate which has a cam which causes the pins to reciprocate radially. The pins reciprocate to an extent which will extend them outwardly from the platen surface a sufficient distance to engage feed holes in stationery and then to fully retract below the surface of the platen. In the present invention, the entire pin feed unit is mounted upon a metal sleeve 10 which fits fairly closely around the platen shaft 8. A pin carrier, generally indicated 11, is mounted to revolve with the sleeve 10 and with the platen surface 9. The pin carrier has a cylindrical part 12 which fits inside of the

rubber covering 9 of the platen and against the metal sleeve 10 which supports the entire unit. The pin carrier is held in place by a washer-like plate 13 abutting the end of the sleeve 10 and fastened to the cylindrical portion 12 of the pin carrier by a pair of cap screws 14 on diametrically opposite sides of the shaft of the platen. The cylindrical portion 12 also has a radial bore 24 in which a driving pin 15 having a square head 16 is mounted so that a positive drive connection will be made between the pin carrier and the rubber surface sleeve 9 of the platen. An appropriate slot is made in the underside of the sleeve 9 to accommodate the square head of the driving pin.

The pins of the feeding member are housed in a radially extending portion 20 of the pin carrier 11. As better seen in Figure 2, the radially extending portion 20 of the pin carrier is provided with radial square grooves 21 which form bearings for pins 25. The slots 21 are milled in the face of the radially extending portion 20 of the carrier and may be ten in number, as illustrated in Figure 2, or in other units may be nine or eleven, equally spaced around the face thereof.

The pins 25 are made of square stock in a screw machine operation which forms a rounded end 26 which is smooth in contour. After the pins have been formed of the square stock, generally of tool steel, they are placed in a jig and cross drilled to form an aperture 27 for the reception of a cam follower pin 28 placed therein with a press fit. All of the pins 25 used in the units are of equal length with the unit being nine, ten or eleven pin type. The stock from which the pins are made is controlled in thickness quite accurately so that the slots 21 may be milled about .002" over the size of the pins. In this manner, a very accurate bearing surface for the square pin is provided in the pin carrier 11.

As mentioned above, the bearings for the pins are open on the face of the pin carrier and the pins reciprocate in the slots. A four-sided apertured bearing is pro-

vided for the pins by closing the open side of the slots with the cam cover plate 30. The slots for the pins are milled about .002" in depth over the thickness of the pins so that the cam cover plate may be practically abutted against the pin carrier without binding the pins in place.

The pins are made to reciprocate in their respective bearings by the cam follower pins 28 riding in a cam groove 31 milled in the face of the cover plate 30. As seen in Figure 3, the follower pins 28 are spaced evenly around the centerline of the shaft 8 and each is in the cam groove 31, the shape of which is illustrated.

In operation, the cam cover plate 30 rides on the metal sleeve 10 and is held in place therein by a ring retainer 32 abutting against a clamp 33 having a shoulder 34 abutting against the ring. The clamp 33, illustrated more clearly in Figure 4, bears down against a slotted end portion 10a of the sleeve so that it may grip upon the shaft 8 to perform the function of making the sleeve 10 rotate with the shaft and to hold the assembly of pin carrier and cam cover plate together against the washer retainer 13 on the opposite end of the sleeve 10. The method used for holding the cam plate stationary while the pin carrier turns is a combination of two control plates mounted on the outer end adjacent the cam plate. One plate 35, better seen in Figure 5, is mounted against the cover plate and held stationary with respect thereto by a screw 36 fastened to the cover plate through an arcuate slot 37 permitting some adjustment of the plate 35 in position relative to the cam plate. A second control plate 38 has an upper open slot 39 for engaging the usual cross rod on a platen used to hold the paper guide. This plate 38 is thus held stationary in position relative with the platen. A latch member 40 is secured to the plate 38 by rivet 41 having a spring washer 42 under its head and a detent for engaging notches 43 in the control plate 35 to in turn hold the cam plate stationary. Upon manual release of the latch by grasping the handle 44, the plate 35 can be manually turned to bring the notch 43 down to the latch member, thus shifting the position of the cam plate 30 relative to the platen. In this manner, the apex portion, generally indicated 31a, of the cam groove, as seen in Figure 3, can be shifted relative to the line of writing on the platen. If the pins are not needed, they may be caused to extend outwardly from the platen at a point that will not contact the stationery.

The complete unit may be removed from the end of a platen quite readily and easily by loosening the clamp 33 by its clamping screw 33a sufficiently to allow the metal sleeve 10 to be slipped longitudinally over the shaft 8 of the platen. It has been found, however, that in the present unit there is little need for removing the unit once installed since there is practically no binding of the pins in the unit at any time even though service of the unit is neglected. The combination of the square pins riding in bearings for practically their full length of travel and the use of the round pin followers riding in a milled cam groove has eliminated all sticking or catching of the pins. Accelerated life tests have indicated that the unit is particularly adapted for long life and use without particular attention or service. The manufacture of the unit, particularly in the assembly stage, is facilitated by the structure of the unit. No difficulties have been encountered in getting the unit to run smoothly after assembly.

The foregoing detailed description has been given for clearness of understanding only, and no unnecessary limitations should be understood therefrom, for some modifications will be obvious to those skilled in the art.

I claim:

1. A pin type stationary feed unit, comprising: a pin carrier having a plurality of apertured bearings extending radially; pins reciprocally mounted in said bearings with the pins and bearings having polygonal cross sections preventing rotary movement of the pin in the bearing, said bearings being elongated and providing the sole guiding support for the pins; a laterally extending stud on each pin; and a plate having a cam groove therein receiving said studs for moving the pins radially upon relative rotation of the carrier and plate.

2. A pin type stationary feeding unit, comprising: a pin carrier having radially extending open grooves in one side; a cover plate closing the open side of said grooves to form apertured radially extending elongated bearings; a feeding pin slidably supported in each bearing with the pin and bearing having complementary polygonal cross sections; and a laterally extending stud on each pin with the cover plate having a cam groove receiving the studs for moving the pins radially in their respective bearings.

3. A pin type feeding unit for continuous form stationery, comprising: a pinwheel and a cover plate having radially extending adjacent faces, said pinwheel face having a plurality of radial grooves therein closed on one side by said cover plate face, said grooves each being shaped to form an elongated square bore apertured bearing; a square pin slidable in each bearing; a laterally extending stud secured to each pin; and said cover plate having a cam groove therein receiving said studs for moving the pins radially in said bearings upon relative rotation of the pinwheel and plate.

4. A pin type feeding unit for continuous form stationery, comprising: a pinwheel and a cover plate having adjacent faces, said face of the pinwheel having radial grooves, said cover plate face closing one side of said grooves and the grooves being shaped to form a plurality of square bores cooperatively with the cover plate; a square pin in each bore having continuous bearing support in the bore for radial reciprocation; and a round laterally extending stud on each pin with said cover plate having a cam groove in said face receiving said studs for moving the pins radially upon rotation of the pinwheel relative to said cover plate.

5. A pin type stationary feeding unit, comprising: a pinwheel and a cover plate mounted side by side for relative rotation; a plurality of feeding pins mounted in the pinwheel and having continuous sliding bearing support therein to confine movement of the pins to radial reciprocation; and a laterally extending stud on each pin extending outwardly from the pinwheel, said cover plate having a cam groove with continuous side walls for abutting said studs for moving the pins radially upon rotation of the pinwheel relative to said cover plate, and said studs having rounded surfaces engaging said cam groove side walls to prevent binding of the studs in the groove during said rotation.

6. A stationery feeding unit as specified in claim 5 wherein the bearing support for the pins comprises square bores formed cooperatively by grooves in the pinwheel and a flat face of the cover plate and the pins are square with only sliding tolerance between the pins and bores.
